[57] CLAIM

The ornamental design for an insulin shot reminder tray, as shown and described.

DESCRIPTION

FIG. 1 is a perspective view of an insulin shot reminder tray showing my new design;

FIG. 2 is a top plan view thereof, and

FIG. 3 is a top plan view of another embodiment of FIG. 1, with the only difference residing in the size of the holes on top of the claimed design; with all undisclosed portions being identical to that shown in FIGS. 1 and 2.

FIG. 1

SUN	MON	TUE	WED	THU	FRI	SAT
○	○	○	○	○	○	○
○	○	○	○	○	○	○
○	○	○	○	○	○	○

FIG. 2

SUN	MON	TUE	WED	THU	FRI	SAT
○	○	○	○	○	○	○
○	○	○	○	○	○	○
○	○	○	○	○	○	○

FIG. 3
